ERNEST G. UNGER, OF NEW YORK, N. Y.

HAIR-WAVING APPARATUS.

Application filed September 4, 1923. Serial No. 660,757.

The invention relates in general to an apparatus for use in practicing the art of waving hair on a person's head, and the invention specifically relates to means for treating the coiled hair during the heating step constituting part of the so-called permanent hair waving treatment.

In practicing the art of permanent hair waving, it is usual to coil a strand of hair on a curling rod, to wet the hair usually with some hair treating solution, to enclose the wet hair in a preformed envelope or tube, and then to slip onto the tube a relatively short electric heater, the heater is customarily positioned close to the person's head so as to confine the waving to that portion of the hair which is adjacent the head of the person under treatment. Usually the hair enclosing tube is formed of paper, or other flexible material; is tied at opposite ends so as to retain the steam or fumes from the hair treating substance used while one end of the coiled hair strand is subjected to the direct action of heat from the heater encircling that portion.

In one aspect of the present disclosure there is featured the substitution of a metal tube in place of the usual paper tube. This substitution is not new per se but in similar prior devices no effort was made to utilize the metal tube as a part of the hair enclosing apparatus for subjecting the coiled hair to the steaming or other fume saturating operation.

Accordingly the invention has for an object in using such metal tubes, the providing of a simple construction which will tend to enclose or substantially enclose the entire length of the curled hair, which, at the same time, will provide a structure one part of which will facilitate the transference of heat from the heater radially to the portion of the coil desired to be heated, and another part of which will constitute an air-cooled radiator which will tend to maintain the portion of the hair exterior of the heater at a temperature lower than the temperature necessary to effect a hair waving operation.

Another object of the invention is to provide a heating device of the type outlined in which all portions of the hair enclosed within the outline of the heater will be uniformly heated. The invention therefore features a simplified construction by means of which the curling rod on which the hair is wrapped will be centered axially within

the heater and in this way the outer cylindrically formed surface of the hair coil is maintained in equally spaced relation to the inner cylindrical wall of the enclosing heater. 60

Considered in its structural aspect the disclosure contemplates primarily the formation of a unitary heating structure which will include a long thin hair containing tube preferably formed of metal, encircled at one end by a relatively short heating unit permanently secured thereto so as to constitute a complete one-piece manufactured unit. There is on the market at present a form of electric heater which has been designed 70 especially to meet the very exacting requirements of a heater for use in this art.

Another object of the invention is to provide a form of tube, as a separate article, designed to be installed and located in the standard forms of heaters now in general use, in such way as to form a type of heater of the class herein featured. In such assembled form of the invention there is the possibility that the portion of the hair enclosed in the tube, and within the outline of the heater, will be unequally heated and accordingly, the invention features a simplified means for insuring the centering of the tube within the replaceable heater. 85

It is required of such devices that the heating unit be positioned as close as is possible to the person's head so as to bring the resulting wave in the hair close to the scalp. Due to the high temperatures that are developed by such heating devices, there is danger of burning the head unless precautions are taken to protect the same. The usual practice is to position a heat insulating shield between the heater and the person's head. Such a shield is also utilized in the present disclosure for protecting the head and further the shield is designed to have the additional function of locating the enclosed portion of the hair closer to the head than has been possible heretofore. The invention accordingly features the use of a protecting shield and a disposition of the heating unit relative to the end of the tube adjacent the head so that sufficient heat will be discharged towards that end of the tube to obtain the maximum waving effect with the least possible heating of the scalp in spite of positioning the heater relatively close to the head. 105

Differently expressed another object of the invention is to provide a simplified

means for securing the heater to the tube in that preset position spaced from but relatively close to the scalp which will attain the maximum heating effect on the hair as close to the head as is possible, while minimizing the heating effect on the head.

Still another object of the invention is to provide a construction in which the several parts can be readily demounted for repair; 10 for cleaning, or for substitution of parts, and which parts will be designed to facilitate a rapid practicing of the mounting of the hair coil in the heater and by means of which the heating unit together with the 15 parts enclosing the hair can be quickly removed and the hair exposed in case of overheating.

Various other objects and advantages of the invention will be in part obvious from 20 an inspection of the accompanying drawings and in part will be more fully set forth in the following particular description of one form of mechanism embodying my invention, and the invention also consists in certain 25 new and novel features of construction and combination of parts hereinafter set forth and claimed.

In the accompanying drawings:

Figure 1 is a view in side elevation showing 30 a preferred embodiment of the invention in position to heat a strand of hair in coiled position.

Figure 2 is an enlarged longitudinal sectional view taken axially through the device 35 shown in Figure 1;

Figure 3 is a transverse sectional view taken on the line 3-3 of Figure 2 looking in the direction indicated by the arrows;

Figure 4 is a view in side elevation of a 40 portion of the tube shown in the preceding figures and with the heater vent removed;

Figure 5 is a view in end elevation of the right hand side of the device shown in Figure 2; and

Figure 6 is a fragmentary view similar to Figure 2 showing a modified form of the invention.

In the following description and in the 50 claims, parts will be identified by specific names for convenience of expression but they are intended to be as generic in their application to similar parts as the art will permit.

The heating device herein disclosed consists primarily of a relatively long, open-end, thin metal tube 10 on one end of which is telescoped an electric heater 11. It will be understood that the heater is of the conventional open end tubular form and preferably has a frictional tight fit on the tube 10. It comprises an inner shell 11, an outer shell 12, between which are positioned heating wires 13 supplied from a cable 14. The outer end of the heater, from which projects 60 the cable 14, is provided with a U-shaped

handle 15 contained largely within the projected outlines of the adjacent end of the heater so as to permit the positioning of a maximum number of heaters on the head at one time. In all respects this heater is of the form of a well known make which is between one and one-half and two and one-half inches fitted on the tube 10 which, to accommodate some strands is usually about 8 to 10 inches long.

It is within the scope of this disclosure to consider the heater and tube as fastened together to form a unitary article, or as shown in Figure 6 the tube 10 may be simply a continuation of opposite ends of the inner shell 11. However, in the present disclosure the more complicated form is illustrated so as to feature a form of construction which will utilize the heaters at present on the market.

In either case it will be noted that the heater 11 is positioned in spaced relation to opposite ends of the tube 10 and is positioned relatively close to the end 17 designed to be disposed adjacent the head. In this way there is provided an annular air space 18 between the heater and the shield 19 hereinafter more particularly described. The opposite end of the heater is positioned a material distance from the outer end 20 of the tube so that a relatively long portion of the tube, between the heater and the outer end, will be exposed to the atmosphere and will constitute, in effect, an air-cooled radiator. From this construction it will be appreciated that the portion of the hair adjacent the head will be intensely heated by the encircling heater but that the outer portion of the hair will be enclosed in a relatively cool part of the tube. In this way 105 it is possible to wave the newly grown hair adjacent the head without affecting the previously waved hair at the outer end of the strand of hair. The end 17 of the tube is outwardly flared as shown at 21 and this flared end is designed to be fitted into a similarly shaped recess 22 formed in the adjacent or other side of the shield 19. From this construction it will be seen that the end of the tube with its contained hair can be brought close to the head and at the same time the head is protected by the shield.

The shield is preferably made of a fibrous, heat insulating material and is in the form of a flat, elongated plate with rounded ends. In the form herein disclosed the shield is of the split type formed in two parts hinged together adjacent one of its rounded ends by an eye rivet 23.

The opposite ends of the two parts are 125 locked in edgewise abutting relation by means of the spring catch 24. It is the intent of this part of the disclosure to provide a structure whereby the shield is held to the tube against accidental displacement but is 130

not held so tightly as to resist a quick demounting of the parts. From the structure disclosed it is apparent that a pull on the tube will cause the contained hair to act on the shield and split the same into open position against the holding action of the spring 24. In case of over-heating or other accidents, the tube and heater can be quickly dismounted from the hair leaving the coil 10 of hair exposed.

The shield is provided centrally thereof with a small aperture 25 designed to have passed therethrough the pencil-like portion of the hair strand adjacent the head. In 15 mounting the parts in position the curling rod 26 is positioned with one end as close as possible to the aperture and may even extend into the same. By means of this construction it is possible to center the rod at 20 its end adjacent the head and maintain the hair equally spaced from the inside of the tube. The end of the curling rod adjacent the aperture is provided with an enlarged short cylindrical head 27 provided at its 25 end with a diametrically extending slot designed to receive the portion of the strand of hair adjacent the head and thus hold the hair strand to the rod. The portion of the curling rod which extends through the end 30 of the tube adjacent the shield is reduced in diameter from the diameter of the head 27 so as to form a constricted neck portion 29. From the constricted neck portion the rod is tapered as shown at 30 and in this 35 respect follows conventional forms of such rod. From this construction it is seen that the end of the rod adjacent the head is centered by the hair extending through the centrally disposed aperture in the centered shield or by being itself extended through 40 the central opening.

It is understood that these rods are of different lengths and extend varying distances along the different length tube 10. For the purpose of centering the outer end 45 of the curling rod there is provided an adjustable centering device 31 movable longitudinally in the tube and designed to engage the outer end 32 of the rod which is 50 preferably rounded to assist in this centering.

In the form of the invention herein disclosed the centering device comprises a conical cup 33 having a diameter at its periphery 55 substantially equal to but slightly less than the internal diameter of the tube. In actual practice the edge of the cup 33 is rough and does not provide a hermetically tight fit with the inside of the tube 11. In either 60 case the cup 33 substantially closes the tube but permits a slight leakage past the cup of the steam and vapor generated in the tube especially when under pressure greater than the atmospheric pressure. The device is held 65 frictionally in adjusted position in the tube

and permitting a slight leakage past the same of the steam and vapor generated in the tube by means of a pair of bowed springs 34 which engage at diametrically opposite points against the inside of the tube. The 70 springs are brought together at their outer end to form a finger piece 35 by means of which the centering device may be manipulated in the tube. In mounting the centering device in position it is understood that after 75 the hair has been curled on the rod and inserted in the tube the centering device is inserted through the opened end 20 and is moved along the tube until the free end of the curling rod is engaged in the bottom or 80 pointed end of the conical cup. The action of the conical surface engaging the free end of the rod will tend to center this end and thus insure the positioning of the curling rod axially in the tube. 85

For the purpose of centering the demountable heater 11 in place, the tube is provided with a pair of spaced apart centering rings 36 and 37 which are secured to the tube and have an external diameter to fit within the shell 11 of the heater adjacent opposite ends thereof. This construction provides an air space 38 between the tube and the heater and any steam or gases which may be formed in this space are permitted to escape through vents 39 extending longitudinally through the rings 36 and 37. 95

These rings also provide a means for mounting a heater retaining means and for mounting a stop for limiting the axial movement of the heater. This spring and stop are conveniently formed in one-piece, and in the disclosure comprise a single length of wire 40 bent back upon itself to provide hair-pin-like structure with two parallel outwardly bowed parts 41 designed to frictionally engage the shell 11, and thus hold the heater to the tube against accidental displacement. The parallel parts are passed through a pair of the aligned vents 39 and have their free ends outturned circumferentially to secure the spring structure in place. The crotch portion 42 of this wire structure is bent radially outwardly to form a stop 43 designed to be engaged by the outer end of 100 the heater as shown in Figure 2. From this construction it is apparent that the heater can be slipped onto the tube prior to the mounting of the shield and is moved longitudinally from right to left of the showing in Figure 2 until the heater engages against the stop 43. When so stopped the spring members 41 are in position engaging the heater along a material length thereof as 105 shown in Fig. 2. 110

In operation and assuming that the heater is formed either as a fixed part of the tube or demountably positioned therein as shown in the preferred embodiment of the invention herein illustrated, the device is ready 120 125 130

for use. The end of the hair strand close to the person's head is passed through the slot at the end of the rod and is then curled on the rod with the thick part of the strand at the constricted neck and the progressively thinner part of the strand wrapped about the tapered portion, following conventional practice. The hair is then treated with some suitable preparation usually used in this art 10 and the coiled hair and rod inserted into the tube. An opened shield is then positioned about the hair at the end adjacent the scalp and close to the scalp if not actually touching the same. The flared end of the tube 15 is then inserted into the recess in the shield and the parts of the shield snapped into closed position thus securing the same to the tube. The conical centering device is positioned in the open end as previously suggested and the construction is ready to have 20 the current supply to the heater turned on and the hair waved as is usual in such operations.

Should it become necessary to quickly remove the parts, due to overheating, the tube 25 is grasped and pulled longitudinally off the curled hair, thus exposing the hair free of both the heater and of the enclosing tube together with its end closures provided by 30 the centering cup and by the shield.

By means of a device of the type herein disclosed it is possible to wave practically the entire strand of hair, if desired, and to wave the hair practically up to the scalp 35 without burning either the scalp or the hair. The projecting part of the metal tube, while enclosing the hair treating steam or fumes, also tends to maintain the outer part of the hair relatively cool or at least at a temperature lower than that necessary to effect a 40 waving operation.

While I have shown and described, and have pointed out in the annexed claims, certain novel features of my invention, it will 45 be understood that various omissions, substitutions and changes in the form and details of the device illustrated and in its operation may be made by those skilled in the art without departing from the spirit 50 of the invention.

Having thus described my invention, I claim:

1. A heating device for waving hair comprising a relatively long metallic tube capable of conducting heat open at opposite 55 ends and adapted to receive and contain a coiled strand of hair, heating means encircling the tube adjacent one end and in spaced relation to the opposite end whereby 60 only one end of the tube is the heated while the other end and the part of the hair strand contained therein are exposed to the cooling effect of the outside air.

2. A heating device for waving hair comprising a long tube having relatively high 65

heat conducting capacity and adapted to contain a strand of coiled hair, heating means located at one end of the tube to intensely heat this end and in spaced relation to the other end, the portion of the tube between the heating means and said other end being exposed to permit air cooling of this portion of the heat conducting tube and of the hair contained therein. 70

3. In a device of the class described, the combination of a thin metallic tube having a length sufficient to contain an entire strand of coiled hair, the end of the tube designed to be positioned adjacent the person's head encircled by a heating means and the outer portion of the tube between said heating means and the outer end of the tube being exposed for air cooling and means at the outer end of the tube for incompletely closing the tube to thus confine the hair strand therein while permitting some gas or vapor leakage from the hair containing part of the tube past said closing means and acting to prevent a free flow of air past the hair strand whereby the portion of the hair strand within the outlines of the heating means is heated to the full capacity of the heating means, and is not subjected to any cooling agency. 80 85

4. In a device of the class described, the combination of a long tube adapted to contain a strand of a person's hair, means having a length less than one-half the length of the tube for heating that end of the tube which is designed to be positioned adjacent the person's head and the other end of the tube formed of metal and constituting a heat radiator exposed for air cooling. 90 95

5. In a device of the class described, the combination of a relatively long metallic tube for containing a strand of hair, a relatively short heating device encircling the tube, said heating device being spaced from both ends of the tube and positioned relatively close to one end of the tube, thus providing a short length of tube between said end and the heating device and providing a relatively long portion of tube between said heating unit and the other end of the tube. 100 105 110

6. In a device of the class described, the combination of a tube of heat conducting material having a bore of uniform diameter from end to end, entirely open at opposite ends and adapted to contain a strand of hair, an electric heater unit separable from the tube and adapted to be telescoped on to one end of the tube and means for locating the heater unit in spaced relation to the other end of the tube thereby to leave said other end exposed for air cooling. 115 120 125

7. In a device of the class described, the combination of a long thin metal tube adapted to contain a strand of coiled hair, and a relatively short electric heater having a 130

length less than one-half the length of the tube and adapted to be telescoped on to one end of the long tube leaving the other end and an adjacent portion of the metal tube 5 exposed.

8. In a device of the class described, the combination of two units each complete in itself, one of said units comprising a metal tube adapted to contain a strand of coiled 10 hair, the other unit comprising an electric heater having a bore extending therethrough of a diameter sufficient to receive the tube and a spring for temporarily securing the units in position against accidental displacement.

9. In a device of the class described, the combination of a metallic tube adapted to contain a strand of hair, an electric heater separable from the tube and adapted to 20 be telescoped on to the tube, means including a spring and a stop for locating the heater on the tube in spaced relation to both ends and in position relatively close to one end and in a materially spaced relation to 25 the other end thereby to leave exposed a large portion of the tube on one side of the heater and at said other end.

10. In a device of the class described, the combination of a tube adapted to contain 30 a strand of coiled hair, an electric heater adapted to be telescoped on to one end of the tube and a stop for locating the heater longitudinally on the tube in fixed position spaced from said end.

11. In a device of the class described, the combination of a tube adapted to contain a strand of coiled hair, a bowed spring carried on the outside of the tube, an electric heater provided with a bore for receiving the tube 40 and spring, and said spring adapted to bear on the portion of the heater defining the bore to hold the heater frictionally to the tube.

12. In a device of the class described, a tube adapted to contain a strand of hair, 45 a bowed spring secured to the outside of the tube for engaging a coacting heater unit and said spring provided with an outwardly projecting part constituting a stop for limiting the movement of the heater unit when moved 50 into telescoping engagement with the tube.

13. In a device of the class described, the combination of a hair containing tube, a pair 55 of rings secured in spaced apart relation on the tube, a spring secured to the rings and bowed outwardly from the tube between the rings.

14. In a device of the class described, the combination of a hair containing tube, a pair of rings secured in spaced apart relation on 60 the tube, a spring secured to the rings and bowed outwardly from the tube between the rings, each of said rings provided with air vents extending therethrough to permit leakage from the space between the rings.

15. In a device of the class described, the

combination of a hair containing tube, a pair of rings secured in spaced apart relation on said tube, each ring provided with a plurality of air vents, and a wire bent back upon itself to form a U-spring with parallel legs 70 having their ends passed through a pair of vents in one of the rings and having the opposite ends of each leg passed through a pair of vents in the other ring and said legs being each bowed outwardly and forming a pair of 75 spring members for frictionally engaging a heater unit telescoping the tube.

16. In a device of the class described, the combination of a hair containing tube, a pair of rings secured in spaced apart relation on 80 said tube, each ring provided with a plurality of air vents, and a wire bent back upon itself to form a U-spring with parallel legs having their ends passed through a pair of vents in one of the rings and having the opposite ends of each leg passed through a pair 85 of vents in the other ring and said legs being each bowed outwardly and forming a pair of spring members for frictionally engaging a heater unit telescoping the tube, and the 90 crotch portion of said wire being bent outwardly to form a stop for limiting the longitudinal movement of the heater unit on the tube.

17. In a device of the class described, the combination of a tube adapted to contain a strand of coiled hair, an electric heater adapted to be telescoped on to one end of the tube and a stop for locating the heater longitudinally on the tube in fixed position 95 spaced from said end, and a shield dismountably secured to said end of the tube and spaced from the heater telescoping the tube.

18. In a device of the class described, the combination of a tube adapted to contain a strand of coiled hair, an electric heater adapted to be telescoped on to one end of the tube and a stop for locating the heater longitudinally on the tube in fixed position 105 spaced from said end, and a shield dismountably secured to said end of the tube and spaced from the heater telescoping the tube, and a split heat insulating shield positioned in spaced relation to the heater to protect the person's head from the heating effect 110 of the heater.

19. In a device of the class described, the combination of a metallic tube adapted to contain a strand of hair and provided on its outer side with a longitudinally spaced apart 120 pair of symmetrical centering rings and a heater having a bore extending therethrough and engaged by the centering rings, said rings acting to maintain all parts of the heater equally spaced from the tube and 125 provided with air vents extending therethrough parallel to the axis of the tube, said heater and metallic tube coacting to provide an air space defined at opposite ends by said air vented heater centering rings. 130

20. In a device of the class described, the combination of two units each complete in itself, one of said units comprising a metal tube adapted to contain a strand of coiled hair, the other unit comprising an electric heater having a bore extending therethrough of a diameter sufficient to receive the tube and a spring for temporarily securing the units in position against accidental displacement.
21. In a device of the class described, the combination of a tube adapted to contain a strand of hair, a curling rod extending axially in said tube, means movable in the tube independently of the rod for centering the rod in the tube and a finger piece secured to said centering means for shifting the same within the tube.
22. In a device of the class described, the combination of a tube adapted to contain a strand of hair, a curling rod extending axially in said tube and a centering device comprising a conical cup having a circular periphery and having its concaved side facing the adjacent end of the rod and providing a surface for guiding said end toward the axis of the tube as the rod and centering device are moved relatively towards each other and axially of the tube.
23. In a device of the class described, the combination of a tube adapted to contain a strand of hair, a curling rod extending axially in said tube and a centering device including a conical seat having a concaved rod guiding surface in said tube adapted to receive one end of the rod to center the same in the tube.
24. In a device of the class described, the combination of a tube adapted to contain a strand of hair, a curling rod extending axially in said tube, a centering device slidably mounted in the tube and engaging one end of the rod to hold said end in spaced relation to the tube and a spring clutching device for holding the centering device frictionally in the tube.
25. In a device of the class described, the combination of an open end tube, a closure at one end provided with an aperture at the center thereof, a curling rod in the tube adapted to be projected at one end through said aperture and thus approximately centered thereby in the tube, and means shiftable in the tube for centering the opposite end of the rod and acting thereon to center the same.
26. In a device of the class described, the combination of an open end hair containing tube, a split shield secured to one end of the tube and substantially closing said end, means within the outlines of the shield for centering the same on the tube and fastening means at the outer edge of the shield for securing the same locked in its centered position on the tube.
27. In a device of the class described, the combination of a tube adapted to contain a strand of hair, a flat shield for substantially closing one end of the tube, said shield provided on one side with a shallow recess of a size to receive the end of the tube and said recessed portion provided with a relatively small aperture adapted to have the hair strand passed therethrough.
28. In a device of the class described, the combination of a tube having an outwardly flared end, a shield having a recess on one side adapted to contain said end of the tube, the part of the shield outlining the side of said recess being slightly undercut to overlap the flared end of the tube.
29. In a device of the class described, a flat shield provided on one side with an annular recess adapted to receive an end of a tube, said shield being in two parts with the jointure between the parts extending diametrically across the axis of the recess.
30. In a device of the class described, a flat shield provided on one side with an annular recess adapted to receive an end of a tube, said shield being in two parts with the jointure between the parts extending diametrically across the axis of the recess, said parts being hinged together and means for securing the parts in position.
31. In a device of the class described, a flat heat insulating shield having a tube receiving annular recess on one side, said recess having a diameter materially greater than its depth, and the portion of the shield forming the bottom of the recess provided centrally thereof with a small aperture, said shield being in two parts split across the aperture and means for securing the parts in position.
32. In a device of the class described, the combination of two separable units, one constituting a relatively long metallic tube adapted to contain a coiled strand of hair and the other constituting a relatively short electric heater complete per se and adapted to be positioned in place telescoping the hair containing tube, said tube with the heater in position projecting beyond one end of the heater and said heater provided with a handle extending substantially parallel to and spaced from the projecting portion of the tube, and substantially centered between opposite ends of the same to provide a means for supporting the heater and tube when assembled at a point approximately mid-length of the assembly.
33. In a device of the class described, the combination of an open end metal tube having a flared end, and a split flat shield provided with a shoulder engaging the flared end for demountably securing the flat shield to the tube at its open end.
34. In apparatus for waving hair, a curler rod on which the hair is wound, a tube in

which said rod with the wound hair is inserted, an imperforate barrier having a circular peripheral edge engaging the tube and tending to prevent the free escape of steam therefrom, said barrier provided with means within said tube, affording frictional engagement with said tube and adapted to receive and hold said rod when inserted in the tube.

35. In apparatus for waving hair; a curler rod on which the hair is wound, a tube within which said rod with the wound hair is inserted, means adapted to be placed across said tube and provided with a group of spring clamping arms adapted to be inserted within the outer end of said tube.

36. In apparatus for waving hair, a tubular member in which a curler with the wound hair thereon may be inserted, a closure for said member provided with resilient arms adapted to be inserted within the said mem-

ber and engage its walls with yielding frictional contact to retain said closure in place.

37. In apparatus for waving hair, a tubular member, a curler-rod on which the hair is wound for insertion in said member, means for engaging said curler-rod and said means being adapted to be inserted in said tubular-member and to frictionally engage under tension the interior walls thereof. 25

38. An apparatus for waving hair, a tubular member, a curler rod on which the hair is wound for insertion in said member, rod locating means within the member for engaging said curler rod and said means including resilient elements frictionally engaging the interior wall of said member. 30 35

Signed at New York in the county of New York and State of New York this 25th day of August A. D., 1923.

ERNEST G. UNGER.
